WASHING MACHINE

George Kuhn, Takoma Park, Md., and Vladimir
A. Grodsky, Washington, D. C.Application November 28, 1931, Serial No. 577,828.
Renewed April 2, 1934

14 Claims. (Cl. 68—37)

The present invention relates to washing machines and has as its general object the provision of a simple machine wherein maximum agitation or circulation of the cleansing fluid is obtained, 5 preferably entirely in the absence of contact with the articles to be washed of moving mechanical parts.

According to the general principle of the invention, a washing compartment is provided 10 through which the cleansing medium, ordinarily water, is circulated by means located externally of the compartment. In the actuation of the device, the water is moved through the compartment first in one direction and then in the opposite direction. More specifically, the invention 15 contemplates a cylinder disposed below the washing compartment and having an activating piston reciprocable therein, the cylinder being in communication at one end with one end of the washing compartment and at the other end with 20 the other end of the washing compartment. In this manner, circulation of the water throughout the washing compartment is assured upon actuation of the piston, the quantity of water 25 placed in the washing compartment upon each movement of the piston naturally depending upon the relative sizes of the washing compartment and cylinder and the stroke of the piston.

While the machine of the present invention is 30 well adapted for manual operation since it affords a maximum effect for a minimum effort, the invention also contemplates the combination with the machine of power actuating means therefor. Any suitable prime mover, such as an 35 electric motor, together with an operating train to cause reciprocation of the activating piston thereby, may be used. As a simple and effective motive means for the activating piston we prefer, in some embodiments of the invention, to use a 40 reciprocating water motor disposed in alignment with the piston and secured directly thereto. We have found by experiment that a water motor constructed generally as hereinafter to be described will develop great power under ordinary 45 pressures and requires a minimum amount of space for installation. The motor comprises a reciprocable piston, which is directly secured to the activating piston so that complicated transmission trains are obviated. A further advantage 50 of the combination is that the same source of water which is utilized to fill the machine is later 55 utilizable to operate it and preferably a distributing valve is provided so that the source may be directed either to the washing compartment to

fill the same or to the motor to operate the machine. An extremely small quantity of water is required for the operation of the motor and if desired, this water may be caught for rinsing purposes.

Due to the fact that the water agitating or circulating means per se is disposed exteriorly of the washing compartment, frangible articles may be washed without danger of breakage. While the machine is admirably adapted to domestic 65 use as both a clothes washer and dish washer, it is not restricted as to size and is well adapted for use in industrial establishments.

Outside of the general features of the invention above discussed, the invention comprises a 70 considerable number of detail features which will appear from the description hereinafter of embodiments of the invention shown in the accompanying drawings. The disclosure herein is merely illustrative of the invention, as will be 75 understood, and is not to be considered as restrictive thereof.

In the accompanying drawings:—

Figure 1 is a vertical section of a manually 80 operable machine constructed in accordance with the present invention;

Figure 2 is a plan view of the machine shown in Figure 1;

Figure 3 is a perspective of details appearing 85 in smaller scale in Figures 1 and 2;

Figure 4 is an elevation of a modified form of 90 washing compartment;

Figure 5 is a vertical section of a modified form of machine embodying a water motor;

Figure 6 is a plan view of the machine of 95 Figure 5;

Figure 7 is a transaxial section of a rotary valve shown in Figure 5 and forming the control means for the reciprocating water motor shown in Figure 5;

Figures 8, 9, and 10 are enlarged sectional views 95 of modified forms of wall portions for the washing compartment;

Figure 11 is an elevation partly in section of a modified form of power driven machine provided 100 with a distributing valve;

Figure 11a is a view of suitable means for connecting the distributing valve of Figure 11 with the source of water supply;

Figure 11b is a section substantially on the line 105 11b—11b, Figure 11.

Figures 12, 13, and 14 are diagrammatical views showing positions of adjustment of the distributing valve of Figure 11; and

Figure 15 is an elevation showing a wringer 110

and mounting in combination with the machine of the present invention.

Referring now to the drawings, and first to Figures 1 to 3, reference numeral 16 designates a container or shell comprising side and bottom walls, the side walls being rectangularly arranged so that the cross section of the container is substantially a square. Within the container 16 is set a cylinder 17, the cylinder preferably having a close fit along vertical lines with the walls of the container so that each imparts rigidity to the other. As clearly shown in Figure 1, the top of the container extends above the top of the cylinder and the bottom of the cylinder proper is spaced above the bottom wall of the container by means of spacing feet as at 18. In effect, the corner portions of the container 16 constitute channel members defining, in conjunction with the wall portions of the cylinder 17, tubular passages connecting the top and bottom of the cylinder.

At a point rather adjacent the lower end of the cylinder than its top, a perforate partition or wall 19 is secured in horizontal position to the cylinder through an integral upturned cylindrical flange 20, union being secured in any suitable manner. Centrally, the partition 19 has fixed thereto a gland or guide sleeve 21 through which is passed a piston rod 22 which extends above the top of the container. Fixed to the lower end of the rod 22 is a piston in the form of a plate 23 which may be suitably reinforced and which has a cylindrical outer flange 24 provided with a circumferential recess for the reception of a packing ring 25, which may conveniently be of rubber tubing or the like.

A perforate cover plate 26 is supportable on the upper edge of cylinder 17, proper seating of the cover plate being secured by means of a depending flange 27 engaging the inner upper margins of the cylinder. Centrally, the cover plate 26 is provided with a gland 28 through which the upper end of piston rod 22 passes.

A flanged cover 29, here shown as being upwardly convex, fits closely over the top of container 16 and when in operative position, engages upwardly extending pedestals 30 secured to cover plate 26 so that the latter is retained in seated position. The extreme upper end of piston rod 22 is passed through a gland 31 mounted centrally of cover 29.

In order to hold cover 29 securely on the top of container 16, as shown in Figure 1, it is provided on opposite sides with pivoted hasps 32 and 33, the hasps having cross portions as at 34, Figure 3, adapted to engage beneath the eccentric cam-like under surfaces of ears 35 presented by brackets as at 36 secured near the upper end of the container 16. Upon swinging the hasps downwardly from the full line position of Figure 3 to the dotted line position, a downward camming action is exerted thereupon, so that cover 29 is drawn tightly against the upper edges of container 16. In order that the hasps may not be accidentally dislodged, ears 35 may be provided with aligned apertures 35' in which are engageable pins as at 37 so that the pins may be positioned outwardly of the hasps in corrugations as at 32'.

Hasp 33 has an extended pintle 38, the outer ends of which are engaged by the arms of a forked link 39 to provide a pivoting axis for the latter. To the other end of the link is pivoted one end of a lever 40 which at a medial portion

is pivotally engaged in the bifurcated upper end of piston rod 22 by means of a pin 41.

Above partition 19, cylinder 17 constitutes the side walls of a washing compartment 42 while below the partition, it defines a piston compartment 43. The upper end of compartment 42 is closed by the perforate cover 26, while the upper end of container 16 is closed by the imperforate cover 29. In operation, starting from the position shown in Figure 1, hasps 32 and 33 are disengaged from their interengaging means and pin 41 removed, whereupon covers 26 and 29 may be slid upwardly and off the upper end of piston rod 22. The articles to be washed are now loaded into compartment 42 and the shell filled with water to a level intermediate the tops of the container 16 and cylinder 17. Hereupon the covers 26 and 29 are replaced and secured and pin 41 reinserted. Upon an upward movement of the free end of lever 40, which is provided with a handle 40', piston 23 rises and lifts the water thereabove. The water intermediate the piston and partition 19 is forced through the apertures of the latter in strong jets which impinge upon and pass through or in contact with the articles in the washing compartment. The water above partition 19 is caused to rise to the extent of the piston stroke and passes through the perforate cover 26 to be drawn downwardly through the corner passages as at 43 and 44, existing between the cylinder and the corners of the container, due to the suction effect at the lower side of the piston. It will be understood that the water passes from the exterior of cylinder 17 to the piston compartment through the openings existing between the spacing feet 18. Upon downward movement of lever 40, a reverse cycle is enforced, water being drawn through the perforations of cover 26 in powerful jets and escaping from the washing compartment through the apertures of partition 19. On the downward stroke of the piston, additional cleansing jets may be secured by providing the upper end of the cylinder 17 with perforations as at 17'.

As shown in Figure 1, the washing compartment and piston compartment have the same cross sectional area. Under these circumstances partition 19 may be advantageously disposed so that the piston stroke is about half the height of the washing compartment. Thus, upon each stroke of the piston, a major portion of the fluid contents of the washing compartment will be displaced, it being remembered that a considerable volume of articles to be washed are in the washing compartment. Consequently, renewal of the water within the washing compartment by the water exterior thereof is constantly effected.

Piston rod 22 is smooth surfaced so as to be without frictional effect on articles within compartment 42 and being the sole moving part within the compartment, it will be understood that the machine is well adapted for use in washing frangible articles, such as dishes, as well as articles of clothing.

A cock 45 is provided at the bottom of container 16 for drainage purposes. If it is desired to give the machine a thorough cleaning subsequent to use, cylinder 17 may be withdrawn from container 16 and the piston, in turn, withdrawn from the cylinder so that access to all parts may be had.

Additional agitational effect may be secured if desired by the utilization of a washing compartment having an intermediate constricted portion

- as indicated at 46, Figure 4. This arrangement is particularly effective where articles of clothing are being washed and the compartment is only partially loaded so as to enable the articles to 5 move upwardly and downwardly under the force of the top and bottom jets and the moving body of water. The units shown in Figure 4 may be set, for example, within the container 16 of Figures 1 and 2, as will be readily understood.
- 10 In Figure 5, reference numeral 47 denotes an outer shell or container and 48 a cylinder, generally similar to the container and cylinder described with reference to Figures 1 and 2. The cylinder, however, while being substantially continuous, comprises upper and lower portions 48' and 49, the upper portion having a perforate bottom 50 whose edges are received on a shoulder formed at the upper end of the lower portion, as shown. Wall 50 is centrally and upwardly offset 15 to form a cylindrical portion 51 concentric with the outer cylinder and inwardly spaced from the walls of the outer cylinder so as to occupy a comparatively small space therein. The cylindrical portion 51 as here shown is provided with a domed top closure wall 52 provided with perforations, and also the outer walls of the cylindrical portion at their upper ends may be provided with perforations as shown. A piston 53 is reciprocable 20 in cylinder 51 and has a depending skirt portion 54 having a sliding fit in cylindrical portion 51 and flared at its lower end, as here shown, to form an integral piston 55 of a size to cooperate with cylinder portion 49. Preferably, piston 55 is provided with radially extending reinforcing ribs as 25 30 35 at 55'.
- The bottom 56 of container 47 is centrally apertured and to the upper margins thereof is secured the circular flange of a base member or casting 57 provided with a downwardly offset portion 57' at its center in which is screwed the lower end of a vertical cylinder 58 constituting the cylinder of a hydraulic motor. A piston rod 59 is passed through a gland 60 at the upper end of cylinder 58 and interiorly of the latter is secured to a piston 61. The upper end of the piston rod is threaded and passed through an aperture in piston 53, the latter being releasably secured to the piston rod between a fixed abutment collar 62 and a wing nut 63.
- 40 45 50 A laterally extending arm 64 fixed to piston rod 59 has secured thereto a depending rod 65 whose lower portion is passed freely through an aperture in the angularly bent end 66 of a rod 67 guided for vertical reciprocation in brackets secured to the side of cylinder 58. The lower end of rod 65 has an abutment element 65' secured thereto.
- The lower end of rod 67 is passed through a 55 60 65 packed aperture 68 in the top wall of member 57 and is pivoted to an oscillatable arm 69 associated with a valve 70 which is shown in detail in Figure 7.
- Referring to Figure 7, valve 70, as here shown, 70 75 comprises a casing 71 provided with four radially directed ports at ninety degree intervals into which are connected the conduits 72, 73, 74 and 75. Within the casing and separating the latter into two compartments by means of diametrically extending vanes is a rotary valve member 76 fixed on a shaft 77 journaled in the casing. Arm 69 swings freely about the axis of shaft 77 and has pivoted to its end a pin 78 slideable in a 80 85 90 guide member 79 pivoted to the end of an arm 80 whose other end is fixed to shaft 77. A compression spring 81 is engaged between guide mem-
- ber 79 and a shoulder adjacent the pivoted end of pin 78, the spring surrounding the pin. As shown in Figure 7, water under pressure entering conduit 72 which is the inlet conduit, is directed to conduit 74 which may be assumed to lead to the lower end of cylinder 58 as indicated in Figure 5. Consequently, piston 61 is forced to rise in cylinder 58 and carries pistons 53 and 55 with it. Piston 55 has the effect already described with reference to Figures 1 and 2, while piston 53 acts to force jets of water through the apertures of its head portion. When abutment member 65' strikes the lower surface of angular portion 66 of rod 67, the latter will be moved upwardly. Eventually the pivot point of pin 78 passes the line of arm 80 and spring 81, which, in the meantime, has been further compressed, snaps arm 80 to a lower limit position wherein the rotary valve member 76 is positioned to connect conduit 72 with conduit 73, the latter leading to the top of cylinder 58, as indicated in Figure 5. Rotary valve member 76, in its new position, also connects conduits 75, 74 with the exhaust conduit so that water under pressure is now entering the top of cylinder 58 and the water beneath the piston 61 is being exhausted. Eventually, arm 64 strikes the angular projection 66 and moves rod 67 downwardly until the pivot of pin 78 passes the line of arm 80, whereupon the latter is snapped back instantaneously to the 100 105 limit position shown in Figure 7.
- From the above description, it will be understood that so long as water under pressure is introduced into valve 70 through conduit 72, piston 61 will be reciprocated and will cause circulation of water through the washing compartment 82. In Figure 5, inlet conduit 72 has been shown as continued through a wall of container 47 so that a supply hose may be attached thereto, and it may be assumed that the exhaust conduit 110 115 120 125 tributor valve generally indicated at 94 is provided. Since this valve embodies a gravity drainage conduit for the container, it is positioned below the latter.

5 The valve 94 comprises a cylindrical casing 95 and an elongated rotary plug which in Figures 12 to 14 is shown as being cut in two parts 96 and 96' for convenience of illustration, the plug being rotatable by means of an external handle 10 and pointer 97' secured thereto. The casing 95 has three radial ports about portion 96 of the plug into which are connected conduits 97, 98, and 99. Similarly, the casing is provided with three ports around plug portion 96' into which 15 are connected conduits 100, 101, and 102, the ports of each series being spaced substantially 90° as here shown. Conduit 97 is the inlet conduit leading from the source of water supply; conduits 98 and 101 debouch into the bottom of 20 container 92; conduit 99 leads to the control valve 70; conduit 102 leads from the control valve; and conduit 100 is the drain conduit.

With the plug in the position shown in Figure 12, conduits 97 and 98 are communicated through 25 a recess 103 in plug portion 96 so that the container 92 may be filled, plug portion 96' closing conduit 101. When the receptacle is filled and the washing operation is to be initiated, the plug is turned to the position of Figure 13 wherein inlet conduit 97 is communicated through recess 103 with conduit 99 and conduit 102 is communicated through a recess 104 of valve portion 96' with outlet conduit 100. The control valve 70 has been fully described above. In Figures 11 30 to 13, however, conduit 99 is the supply conduit in direct communication with the valve and conduit 102 the exhaust conduit, these corresponding respectively to the conduits 72 and 75 of Figure 7. Conduits 99' and 102', Figures 11 to 13, correspond 35 respectively to conduits 73 and 74 of Figures 5 and 7. When the washing operation has been completed, the valve plug is turned to the position of Figure 14 wherein conduit 101 is communicated with outlet conduit 100 through the recess 104 and the container is drained, conduits 97 and 98 being closed by plug 96.

In many plumbing installations, the hot and cold water supply may be drawn through a single spigot and under such circumstances, the supply 50 conduit 97 may be connected to the spigot by means of a section of rubber tubing 105, Figure 11a. Any suitable means may be provided for connecting the tubing with the spigot and if the latter is unthreaded, a tension band 106 may be utilized. Where there are two faucets, one for 55 hot water and one for cold, a forked section of metal tubing 107 may be inserted in the end of tubing 105, the branches of the metal tubing section having flexible tubing sections 108 and 109 slipped thereover and securable to the spigots by means of tension bands 110 and 111, or in 60 any other suitable manner. In either instance, the hot water supply may be led to the container and the cold water supply to the motor without 65 disturbing the connecting means.

In order that the jets issuing from the lower 70 wall of the washing compartment may strike the articles to be washed with considerable force, we have provided the grill 83, Figure 5, and the grill 112, Figure 11. If articles of clothing are to be washed, it is sometimes desirable to restrain the mass against vertical movements and if less than a full load is in the cylinder 113, Figure 11, grill 112 may be elevated to the proper position 75 and secured therein by means of spring hooks

as at 114 and 115 adapted to engage in apertures 116 and 117 of vertically extending rows formed in cylinder 113.

When a simple perforate wall such as at 50, 80 88, etc., of Figure 5, for example, is provided, there is a tendency for the jets to spread, due to lateral eddies. The strength of the jets can be greatly increased if each perforation is in the form of a tubular protuberance as at 118, Figure 8, the protuberances acting as nozzles. In Figure 9, the protuberances 119 are shown as being inclined to the plane of the perforate surface so as to have a tendency to move the articles in the washing compartment around the axis of the latter. A similar effect is secured in Figure 10, wherein the plate or wall element 120 is provided with inclined radial slots 121.

Various effects can be secured by predetermined dispositioning of the perforate surfaces. For example, in Figure 5, the head of cylindrical portion 55 is adapted to direct jets of water throughout the upper portion of the washing compartment. This effect is very desirable where articles such as dishes are to be washed. Obviously, dish racks may be provided in which the dishes are arranged, the racks being shaped to fit into the washing compartment and being readily insertable and removable.

In Figure 15 we have shown a wringer provided with means for attachment to the top of the described containers or outer shells. In this figure the container may be assumed to be that of Figure 1 for purposes of description. The wringer designated at 122 is mounted on a flat support 123, such as a board, which at its ends 105 is provided with hasps 124 and 125 engageable with the brackets 36 in the same manner as hasps 32 and 33 described with reference to Figure 1.

It will be seen that we have provided an extremely simple machine wherein provision is made for a maximum water circulation. Water is powerfully impelled through the washing compartment in opposite directions and in auxiliary variously directed jets as desired. Further, the 110 water within the washing compartment proper is constantly renewed by the water in the container outside of the washing compartment. As an illustration of this latter point, assume that the piston stroke, Figure 11, is half the height 115 of the water compartment and that the container 92 is filled. Even with no articles to be washed in the washing compartment, it will be evident that upward movement of the piston will displace half of the water in the washing compartment and downward movement of the piston will cause the remaining half to move into the piston compartment so that the washing compartment will be entirely filled with water 120 drawn from the external passages. Further upward movement of the piston causes the water in the piston compartment to be powerfully injected into the washing compartment to mix with the water therein.

While we have described the features of our 125 invention in considerable detail in order to enable the invention to be readily practiced, we desire to repeat that we do not limit ourselves to the disclosure herein, either as regards details of construction of the washing machine per se or as to the nature of the operating power to be used in combination herewith. Many 130 changes may be made without departure from the scope of the following claims which define the invention.

In the claims, unless otherwise specified, the "perforate partition" or "perforate bottom" recited may be assumed to be of construction suitable to support the articles in the washing compartment and communicate the latter with the activating piston chamber.

We claim:—

1. A washing machine comprising upper and lower cylindrical portions separated by a perforate partition, said partition having an upwardly extending cylindrical portion centrally thereof and spaced from the walls of said upper cylindrical portion, a piston in said lower cylindrical portion and a piston in said upwardly extending cylindrical portion, means for reciprocating said pistons in unison, and a fluid communicating passage between the lower end of the lower cylindrical portion and the upper end of the upper cylindrical portion. 80
2. A washing machine comprising upper and lower cylindrical portions separated by a perforate partition, said partition having an upwardly extending cylindrical portion centrally thereof and spaced from the walls of said upper cylindrical portion, a piston in said lower cylindrical portion and a piston in said upwardly extending cylindrical portion, means for reciprocating said pistons in unison, and a fluid communicating passage between the lower end of the lower cylindrical portion and the upper end of the upper cylindrical portion, said upwardly extending cylindrical portion having laterally directed perforations at its upper end. 85
3. A washing machine comprising upper and lower cylindrical portions separated by a perforate partition, said partition having an upwardly extending cylindrical portion centrally thereof and spaced from the walls of said upper cylindrical portion, a piston in said lower cylindrical portion and a piston in said upwardly extending cylindrical portion means for reciprocating said pistons in unison, and a fluid communicating passage between the lower end of the lower cylindrical portion and the upper end of the upper cylindrical portion, said upwardly extending cylindrical portions having laterally directed perforations at its upper end and being provided with a perforate top closure. 90
4. Structure according to claim 1 wherein one of the pistons has a depending skirt portion radially expanded at its lower end to form the second piston. 95
5. Structure according to claim 1 wherein one of the pistons has a depending skirt portion radially expanded at its lower end to form the second piston, the piston reciprocating means being disposed at least partially within said skirt portion. 100
6. In a washing machine, a washing compartment, means for circulating water in said compartment, a water motor operatively connected to said means, and means including a distributing valve selectively adapted in one position of adjustment of the valve to deliver water to said compartment, in another position to deliver water to said motor and to pass the exhaust from the motor, and in still another position to drain said compartment. 105
7. A machine of the class described comprising an upright cleaning compartment having a perforate bottom, said perforate bottom being vertically adjustable and means being provided for retaining the same in adjusted position through engagement with the walls of said compartment, a cylinder below the said compartment, means providing fluid passages between the ends of the cylinder and the top and bottom of said compartment respectively, a piston in said cylinder substantially filling the same transversely, and means for reciprocating said piston to force liquid back and forth through said passages and said compartment. 110
8. A machine of the class described comprising an upright container having bottom and side walls and being substantially polygonal in cross section, a substantially continuous upright cylinder within said container and having upper and lower edges spaced below the top and above the bottom of the container respectively whereby passages are defined between the cylinder and the corners of the container, said passages connecting the top and bottom of the cylinder, a perforate partition dividing the cylinder into upper and lower compartments of which the top compartment is a cleaning compartment, a piston in the lower compartment substantially filling the same transversely, and means for reciprocating the piston to force liquid back and forth in said upper compartment. 115
9. A machine of the class described comprising an upright container having bottom and side walls and being substantially polygonal in cross section, a substantially continuous upright cylinder within said container and having upper and lower edges spaced below the top and above the bottom of the container respectively whereby passages are defined between the cylinder and the corners of the container, said passages connecting the top and bottom of the cylinder, a perforate partition dividing the cylinder into upper and lower compartments of which the top compartment is a cleaning compartment, a perforate cover for said cylinder, a piston in the lower compartment substantially filling the same transversely, and means for reciprocating the piston to force liquid back and forth in said upper compartment. 120
10. A machine of the class described comprising a compartment having a top loading opening and a perforate bottom for the support of articles to be treated, a vertical cylinder below said compartment with its top end in fluid communication with said compartment through said perforate bottom, there being a passage connecting the bottom of the cylinder with the top of said compartment, a piston in said cylinder substantially filling the same transversely, and means for reciprocating said piston whereby upon movement of the piston in one direction liquid in the cylinder above the piston is delivered to one end of said compartment and liquid in said compartment is simultaneously withdrawn from the other end thereof into the cylinder below the piston, the fluid movement being reversed upon movement of the piston in the opposite direction. 125
11. A machine of the class described comprising a walled compartment having a top loading opening and a perforate bottom for the support of articles to be treated, a vertical cylinder below said compartment with its top end in fluid communication with said compartment through said perforate bottom, a vertically extending channel element defining a tubular passage in conjunction with the compartment wall, said passage connecting the bottom of the cylinder with the top of said compartment, a piston in said cylinder substantially filling the same transversely, and means for reciprocating said piston whereby upon movement of the piston in one direction liquid in the cylinder above the piston is delivered to one end 130
12. A machine of the class described comprising an upright cleaning compartment having a perforate bottom, said perforate bottom being vertically adjustable and means being provided for retaining the same in adjusted position through engagement with the walls of said compartment, a cylinder below the said compartment, means 135
13. A machine of the class described comprising an upright cleaning compartment having a perforate bottom, said perforate bottom being vertically adjustable and means being provided for retaining the same in adjusted position through engagement with the walls of said compartment, a cylinder below the said compartment, means 140
14. A machine of the class described comprising an upright cleaning compartment having a perforate bottom, said perforate bottom being vertically adjustable and means being provided for retaining the same in adjusted position through engagement with the walls of said compartment, a cylinder below the said compartment, means 145
15. A machine of the class described comprising an upright cleaning compartment having a perforate bottom, said perforate bottom being vertically adjustable and means being provided for retaining the same in adjusted position through engagement with the walls of said compartment, a cylinder below the said compartment, means 150

of said compartment and liquid in said compartment is simultaneously withdrawn from the other end thereof into the cylinder below the piston, the fluid movement being reversed upon movement of the piston in the opposite direction.

12. A machine of the class described comprising upper and lower substantially cylindrical portions of substantially the same diameter disposed on a common vertical axis, the upper cylindrical portion having a top loading opening, a perforate wall for the support of articles to be treated separating said cylindrical portions, there being a passage connecting the lower end of the lower cylindrical portion with the upper end of the upper cylindrical portion, a piston in said lower cylindrical portion substantially filling the latter transversely, and means including a motor below said piston for reciprocating the same, whereby upon movement of the piston in one direction, liquid in the lower cylindrical portion above the piston is delivered to one end of the upper cylindrical portion and liquid in the latter is simultaneously withdrawn from the other end thereof into the cylinder below the piston, the fluid movement being reversed upon movement of the piston in the opposite direction.
13. A machine of the class described comprising upper and lower substantially cylindrical portions of substantially the same diameter disposed on a common vertical axis, the upper cylindrical

portion having a top loading opening, a perforate wall for the support of articles to be treated separating said cylindrical portions, means extending longitudinally of said cylindrical portions and defining wall portions of a plurality of tubular passages connecting the lower end of the lower cylindrical portion with the upper end of the upper cylindrical portion, a piston in said lower cylindrical portion and substantially filling the latter transversely, and means including a motor below said piston for reciprocating the same whereby upon movement of the piston in one direction, liquid in the lower cylindrical portion above the piston is delivered to one end of the upper cylindrical portion and liquid in the latter is simultaneously withdrawn from the other end thereof into the cylinder below the piston, the fluid movement being reversed upon movement of the piston in the opposite direction.

14. In a machine of the class described, a cleaning compartment, means for circulating water in said compartment, a water motor operatively connected to said means, a distributing valve connectible to a source of water supply, a connection for fluid between the distributing valve and the motor, and a connection for fluid between the distributing valve and the compartment, said last named connection being independent of the first.

GEORGE KUHN.
